DESIGN FOR ROOFING

Application filed November 23, 1932. Serial No. 46,132. Term of patent 7 years.

To all whom it may concern:

Be it known that we, RICHARD S. STREETER and OTTO E. HENDRICK, citizens of the United States, and residents, respectively, of the cities of Oakland and Alameda, county of Alameda, State of California, have invented a new, original, and ornamental Design for a Roofing, of which the following is a specification, reference being had to the accompanying drawing, forming part thereof.

Figure 1 is a side elevation of a fragmen-

tary detail of the shingle used in constructing the design of our invention as shown in Figure 2.

Figure 2 is a side elevation showing the fragment shingles assembled to provide the roofing design of our invention.

We claim:

The ornamental design for a roofing substantially as shown.

RICHARD S. STREETER.
OTTO E. HENDRICK.
